UNITED STATES PATENT OFFICE

STEPHEN M. JENKS AND HARRY H. SUTHERLAND, OF GARY, INDIANA, ASSIGNEES TO
AMERICAN SHEET AND TIN PLATE COMPANY, A CORPORATION OF NEW JERSEY

HEATING FURNACE

Application filed January 22, 1931. Serial No. 510,544.

This invention relates to heating furnaces broadly and more particularly to continuous furnaces for heating metal sheets and packs of sheets.

5 The present improved type of furnace has a furnace chamber constructed so as to have a heating zone and soaking zone. The gases or products of combustion are gradually brought into more intimate contact with the 10 sheets as they pass through the heating zone and the walls of the heating zone are constructed so as to reflect the heat and flame back toward the charging end of the heating zone, resulting in increased efficiency and 15 economy in furnace operation.

In its preferred construction, the furnace chamber is gradually decreased in cross-sectional area from the charging extremity toward the discharge extremity for approximately 20 half of the length of the furnace. At its discharge extremity the chamber is reduced to such dimensions as will bring the gases or products of combustion into intimate contact with the sheets or packs of sheets, 25 resulting in a uniform temperature throughout the sheets and economy in fuel consumption.

At its charging extremity, the furnace chamber reaches its maximum height and 30 from this point the roof and preferably one or both of the walls slope downwardly and inwardly to a predetermined point approximately midway of the length of the chamber forming the heating zone or chamber. By 35 constructing the walls of the heating zone or chamber in this manner, the heating gases are brought into more dense relation as they cool and into more intimate contact with the sheets, and the heat from the gases is reflected 40 by the sloping walls back to the charging extremity of the furnace chamber where the cold sheets enter and at which point the most heat is utilized, and when the sheets reach the relatively reduced portion of the furnace 45 chamber forming the soaking zone, they are subjected to a soaking heat.

The preferred manner of constructing the furnace to bring about the foregoing and other advantageous results is shown in the 50 accompanying drawings, wherein:

Figure 1 is a sectional plan view of a furnace embodying the features of the invention.

Figure 2 is a view in section and side elevation taken on the line II-II, Fig. 1. 55

Figure 3 is a transverse sectional view taken on the line III-III, Fig. 1.

The reference numeral 5 designates the furnace chamber of the furnace and 6 the conveyor rolls for advancing the sheets or packs 60 of sheets, which travel through the furnace in the direction indicated by the arrows. The walls of the furnace may be constructed of the usual refractory material such as brick and supported by steel framework as at 7. 65 The conveyor as shown is of the conventional type well known in the art.

A burner 8 is mounted at one side of the forward end wall of the furnace so as to deliver products of combustion directly into 70 the heating chamber 5, and at the rear of the furnace is a vertical flue 9 for the waste gases, said flue connecting by a conduit 9^a with a stack 10. A preheater for preheating the air supplied to the burner 8 may also be mounted 75 at the rear of the furnace in the vertical flue 9.

The roof of the furnace is indicated at 12 and its contour is clearly shown in Fig. 2. At 80 the charging extremity of the furnace chamber the roof is highest and from this point slopes downwardly toward the rear or discharge extremity of said chamber, for approximately half the length of the furnace, forming what has been termed the heating zone or chamber. The one side wall of the 85 furnace, indicated at 13, is offset at the forward extremity of the furnace chamber, and the gases and products of combustion are fired directly into the furnace at this point, the said wall sloping inwardly or converging to 90 a point approximately intermediate or past the intermediate portion of the chamber. In other words, the furnace chamber is gradually narrowed or decreased in cross-sectional area from the charging extremity to a suitable point midway of the rear or discharge extremity by gradually sloping the roof and side wall. The roof 12 of the furnace chamber from the end of the sloping portion to the 95 discharge end of the chamber is relatively 100

close down to the work passing through the chamber and is of constant height, so as to form what has been termed a soaking zone or chamber.

5 The low roof over the discharge half of the furnace chamber brings the gases or products of combustion into intimate contact with the sheets or packs of sheets, resulting in a soaking effect and a uniform temperature 10 throughout the sheets and economy in fuel consumption. The sloping roof and side walls reflect the heat back to the charging extremity of the furnace where the cold sheets enter and also produce a streamline flow of 15 the gases or products of combustion. The burner fires directly into the furnace against the upper sloping side wall and the heat is reflected into the body of the furnace and also back to the charging extremity of the chamber. 20 The reflection of the heat by the sloping walls of the rear or charging half of the furnace, termed the heating furnace, causes intense heating in this area, while the heat from the products of combustion passing through 25 the forward or discharge half of the furnace chamber, termed the soaking zone, is sufficient to permit soaking rather than heating of the sheets or packs.

What we claim as new is:—

30 A continuous heating furnace for metal sheets and packs provided with a chamber having a relatively high roof at the charging end of the chamber, said roof sloping from the charging toward the discharge end of the 35 chamber to a point approximately midway of the length of said chamber, the roof over the remainder of said chamber being of relatively constant height, at least one side of said chamber being offset at the charging end of 40 said furnace and having a side wall along said offset portion sloping inwardly from the charging end of said furnace to a point approximately midway the length of said furnace, and a burner mounted at the charging 45 end of said chamber and arranged to deliver products of combustion into the offset portion of said chamber and against the sloping roof and side wall along said offset portion of said chamber.

50 In testimony whereof, we have hereunto set our hands.

STEPHEN M. JENKS.
HARRY H. SUTHERLAND.
